UNITED STATES PATENT OFFICE

JOHN R. GAMMETER, OF AKRON, OHIO, ASSIGNOR TO THE GEORGE W. PERKS COMPANY,
OF AKRON, OHIO, A CORPORATION OF OHIO

ABRASIVE WHEEL

Application filed December 10, 1928. Serial No. 325,041.

This invention relates to abrasive wheels and procedure for making the same.

The general purpose of the invention is to provide abrasive wheel construction of the type in which face plates or discs are so bonded to the faces of the emery or other abrasive wheels as to reduce the tendency of the wheels to break apart and, if breakage occurs, to prevent broken parts from flying off the wheel and injuring workmen or destroying property.

More particularly the present invention has for its object the substitution of discs of wire for the metal plates and the provision of effective procedure and means for securing such wire discs upon the faces of the abrasive wheel. The wire discs provide a simple construction permitting reduction in the diameter of the face plates or discs as the wheel wears in a manner similar to that disclosed in the second-named application referred to above.

The foregoing and other objects of the invention are attained in the abrasive wheel constructions illustrated in the accompanying drawings and described below. It is to be understood that the invention is not limited to the specific forms thereof shown and described.

Of the accompanying drawings,

Figure 1 is an elevation of an abrasive wheel embodying the invention;

Figure 2 is a section on line 2-2 of Figure 1;

Figure 3 is an enlarged detail portion of the sectional view shown in Figure 2;

Figure 4 is a side elevation, partly broken away, of a modified form of the invention;

Figure 5 is a diametral section of line 5-5 of Figure 4; and

Figure 6 is an enlarged detail of a portion of the sectional view shown in Figure 5.

Referring to the drawings, the numeral 10 designates a wheel of abrasive material, bonded by a ceramic, rubber or other suitable binder, and which is formed on one or both faces, either during the molding of the wheel or by cutting therein after burning, with grooves preferably spiral in formation. The spirals on the opposite faces are

preferably right and left-hand with respect to the faces on which they are formed.

High tensile wire 12, which may be brass-plated so as to bond with certain plastic materials to be mentioned, is tightly wound spirally in said grooves. The wire may be heated while winding so that upon cooling, shrinkage further tightens the wire. The ends of the wire are clamped and the faces of the wheel on which the wire is wound are cemented and layers 13 of tough, plastic material adapted to be cured or indurated, such as rubber or its equivalents including phenolic condensation products or other artificial resins or rubber substitutes, are applied to the faces of the wheel over the wires. The rubber or equivalent layers are then vulcanized, indurated or cured under pressure to flow about the wire, and into the grooves and interstices in the wheel, causing the wire to be bonded to the surfaces of the wheel.

The wire bonded to the faces of the wheel as disclosed in the present case functions in the manner of the metal plates disclosed in my previous applications referred to in that breakage of wheels so constructed is reduced and when breakage does occur, broken pieces of the wheel are prevented from flying off and injuring workmen or destroying property. In addition, the wire discs disclosed herein are easily reducible in diameter as the wheel wears since the outer convolutions of the wire can be removed without affecting the bond of the remaining convolutions of wire with the faces of the wheels.

In Figures 4, 5 and 6, the present invention is shown embodied in a construction including an abrasive wheel 15 and discs comprising preferably spiral wire convolutions 16 held in place by radial interlacing wires 17 and bonded to the faces of the wheel 15 by rubber or equivalent layers 18. This eliminates the necessity for the grooves in the faces of the wheels.

In use, the wheel is preferably driven in the direction indicated by the arrow in Figure 1, that is, in the same direction as that which the wheel would be driven to wind the wire thereon.

It will appear from the foregoing that by

the invention, an abrasive wheel is simply and inexpensively, but effectively, constructed to reduce breakage and increase the safety of workmen and property endangered by
5 breaking of wheels, and that the facing discs for the wheel are reducible in diameter when the wheel is worn down close to the discs. The invention, in effect, provides a facing of tough, plastic material cured or indurated
10 onto the wheel and containing a wire reinforcement. Obviously, modifications of the invention other than those disclosed herein may be resorted to without departing from the spirit of the invention or the scope of the
15 appended claims.

What is claimed is:

1. An abrasive wheel construction including an abrasive wheel body formed with spiral grooves in its opposite faces, wire convolutions wound while hot in said grooves and permitted to shrink therein, and layers of tough, plastic material cured under pressure over said wire convolutions to bond the wire convolutions to the faces of the wheel.
20
2. An abrasive wheel construction including an abrasive wheel body formed with spiral grooves in its opposite faces, said grooves being right and left hand spirals with respect to the faces in which they are formed, convolutions of wire in said grooves, and layers of tough, plastic material cured under pressure over said wire convolutions to bond the wire convolutions to the faces of the wheel.
25
3. An abrasive wheel construction including an abrasive wheel body formed with grooves in a face thereof, convolutions of wire in said grooves, and a layer of tough, plastic material cured under pressure over said wire convolutions to bond said convolutions to the wheel body.
